United States Patent

Des. 237,390
Patented Oct. 28, 1975

237,390

ELECTRONIC EQUALIZER

Elwood G. Norris, 1520 Canterbury Drive,
Salt Lake City, Utah 84108

Filed July 13, 1973, Ser. No. 379,090

Term of patent 3½ years

Int. Cl. D14—01

U.S. Cl. D26—14 L

FIG. 1

FIG. 4

FIG. 6

FIG. 3

FIG. 2

FIG. 5

FIG. 7

FIG. 1 is a perspective view of an electronic equalizer, showing my new design;

FIG. 2 is a front view thereof on a reduced scale;

FIG. 3 is a left side view thereof on a reduced scale;

FIG. 4 is a rear view thereof on a reduced scale;

FIG. 5 is a right side view on a reduced scale;

FIG. 6 is a top plan view thereof on a reduced scale;

and

FIG. 7 is a bottom plan view thereof on a reduced scale.

The center portion of the casing and the side panels contrast in color, and also in texture as indicated.

The cord and plug are omitted in FIGS. 1-6 for convenience of illustration.

I claim:

The ornamental design of an electronic equalizer, substantially as shown and described.
